UNITED STATES PATENT OFFICE.

OTTO W. JOHNSON, OF OAKLAND, CALIFORNIA.

STAPLE.

Application filed April 9, 1924. Serial No. 705,188.

My invention relates to driven stays or fastenings made of wire, and more particularly to staples, for use in the construction of forms for concrete structures.

5 In the construction of forms for the vertical walls of proposed concrete buildings, much difficulty is experienced in securing the form-boards to the supporting upright studding and especially so if the walls of the 10 form are to be spaced apart for a narrow or thin concrete wall. As now practiced the inner or near wall of the form is nailed to the studding from the inside of the allotted space for the concrete wall, and if this space 15 is narrow the welding of the hammer is restricted, making the erection of the wall and the driving of nails slow and tedious. Also as the nails are, in such cases, driven in on an angle, much unnecessary indentation of 20 the hammer head in the form-board results, marring the finished concrete wall to that extent as the inside surface of the form is the outside surface of the concrete wall.

To rectify the above deficiencies is one of 25 my objects. A further object is to enable a wall-form to be erected rapidly as compared to the present practice, and an equally important object is to enable the wall-form to be torn down or stripped rapidly.

30 Also another important object is the preservation of the form-boards and the studding, as with the use of my invention no nails at all are driven into the boards or studding to mar or split them. The stripped timbers being free of projecting nails are clean or easily cleanable, thus the saving of lumber and nails is considerable and desirable.

35 A further object is the conservation of my staples, as I have made provision for the quick and easy removal of them from the timbers without the danger of bending them, thus they may be used over and over again.

I attain the above objects by the novel 40 construction of my fastening staple, and other objects and advantages of my invention will appear in the subjoined description of the accompanying sheet of drawings, in which:

45 Figure 1 is a view in elevation showing my device in use; the form-boards and concrete are shown in section.

Fig. 2 is a plan of the lower form-board and studding of Fig. 1 showing my device 50 in engagement therewith.

Figs. 3 and 4 are side and face views respectively of the staple of Figs. 2 and 1 on an enlarged scale.

Figs. 5 and 6 are views similar to Figs. 3 and 4 of a modification of the invention, 60 and likewise Figs. 7 and 8 represent another modification.

Adverting to the drawing and figures thereof: the numeral 9 represents in elevation a portion of a vertical concrete wall 65 which has been poured into the customary wooden form indicated by boards 10 and 11. The wall shown is a narrow one, say 6 inches wide, showing how difficult it would be in the erection of the form to secure the inner 70 form-boards 10 to the vertical supporting studding 12 by driving common nails into the studding and at right angles thereto through the latter form-boards, as welding the hammer in the allotted 6 inch space is 75 too limited for efficient results.

My invention advantageously meets the above problem, and the same consists of a wire structure formed substantially in the shape of the letter T looking from the face 80 side thereof as shown in Figs. 1, 4 and 8, and in the shape of a broad and shallow U as shown in Figs. 2, 3 and 7. In the just recited figures showing the face view of my staple, the cross-bar 13 is preferably bent 85 back upon itself substantially to its midway position and is here turned over the said bar from the outside and at right angles thereto as at 14 to form the shank 15, and which shank is of sufficient length to cross 90 the form-boards 10 and project a goodly distance thereover for driving the staple into the body of the studding 12.

In the figures showing the side view of the staple, it will be observed that the free 95 ends of my staple terminate in pointed prongs 16 and 17 substantially positioned at right angles to each other but not in the same plane, 16 being a stub prong for a purpose to be presently set forth, and 17 a 100 prong of longer length and formed with a slight obtuse angle to the major portion of the shank 15 for a purpose also to be presently set forth.

18 is the head of the driving leg or prong 105 17 and is formed to outstand from the surface of the studding when the said prong is driven to securing position in the studding, leaving a space 19 suitable for the entrance of a tool, such as the claw of a hammer, 110

for quick and convenient removal of the staple from the studding in the stripping of the form from the wall after the concrete has set. In Fig. 7 the head 18 is formed by the recurving of the shank 15 as at 20. In this figure the dot-and-dash line 21 represents a surface upon which the head 18 abuts or stops, leaving an equivalent space 19 and for the same purpose.

10 The modified staple shown in the Figs. 5 and 6 is cheaper to construct as the bar 22 does not cross the shank 15, but this form is not as efficient as the preferred form of staple shown in the preceding figures.

15 In operation, the use of my staple in the erection of the form-wall is as follows: The studding 12 and lowermost form-board having been positioned, my staple is laid on the top edge of the said board with the cross-bar 13 or bar 22 placed vertically, and the head of the stub prong 16 is tapped by the hammer for engagement to the board. This prong prevents the staple from falling or turning and insures the holding of the same

20 in position to said board while the workman, with hands freed from the staple, adjusts himself to drive the head 18 of the other prong in any convenient manner. Driving the latter prong, which as previously stated forms preferably an obtuse angle to the major portion of the shank 15, causes the form-boards to be drawn close to the studding by reason of the angle being spread. Before the head is driven home, the upper

25 form-board is positioned against the studding and slid to position between the studding and the upper half of the cross-bar, then the final driving is done, the contiguous elements being drawn together in rigid holding relation. The shank 15 crossing and

bearing on the cross-bar 13 as at 14 equalizes the bearing stress on both form-boards alike.

What I claim as new and desire to secure by Letters Patent of the United States is 45 the following:

1. A staple of the class described comprising a shank portion bent to form a pair of sharpened pronged ends disposed in different planes relative to said shank portion, one 50 of said pronged ends being of less length than the other and disposed substantially parallel to said shank portion and each of said prongs adapted to be driven into holding position.

2. A staple of the class described formed in the shape of the letter T having one end of its cross-bar turned substantially at right angles to said cross-bar, and the free end of the shank turned angularly to said shank to 60 form a driving leg for the staple, and the head of said driving leg so formed as to extend from the surface into which the said leg is driven for the introduction of a tool to remove the staple leg after service.

3. A T-shaped staple formed of wire, the cross-bar of the T being bent back upon itself substantially to its midway position and then back over said bar to form the shank of the T, the bar terminating in a 70 stub end at right angles to the cross-bar and forming a prong, and the shank terminating in a second prong at an obtuse angle to the shank, said second prong being provided with a driving head so that both prongs may 75 be driven into structural elements having surfaces at right angles to each other to secure said elements to each other.

In testimony whereof I affix my signature.
OTTO W. JOHNSON.
